US00D706358S

(12) **United States Design Patent**
Yamamoto et al.

(10) **Patent No.:** US D706,358 S
(45) **Date of Patent:** ** Jun. 3, 2014

(54) **ELECTRONIC COMPUTER**

- (71) Applicant: **Nintendo Co., Ltd.**, Kyoto (JP)
- (72) Inventors: **Shinji Yamamoto**, Kyoto (JP); **Fumiyoishi Suetake**, Kyoto (JP); **Masato Ibuki**, Kyoto (JP); **Kenichiro Ashida**, Kyoto (JP); **Noboru Wakitani**, Kyoto (JP); **Hiroki Ikuta**, Kyoto (JP); **Xiaoming Jin**, Kyoto (JP); **Junji Takamoto**, Kyoto (JP)
- (73) Assignee: **Nintendo Co., Ltd.**, Kyoto (JP)
- (**) Term: **14 Years**
- (21) Appl. No.: **29/455,454**
- (22) Filed: **May 21, 2013**

(30) **Foreign Application Priority Data**

- Nov. 26, 2012 (JP) 2012-028843
- (51) **LOC (10) Cl.** **21-01**
- (52) **U.S. Cl.**
USPC **D21/332; D21/330**
- (58) **Field of Classification Search**
USPC ..... D21/324, 332, 333, 328; 273/148 B;
463/1, 29-35, 46, 47; D14/496;
345/156-161
